UNITED STATES PATENT OFFICE

ABRAHAM L. JONES, OF LOGANSPORT, INDIANA

COMBINATION DOOR AND WALL BED

Application filed May 13, 1929. Serial No. 362,564.

This invention relates to a so-called in-door bed and a receptacle therefor.

The chief object of this invention is to mount a single so-called standard width door so that it may completely close an opening to a receptacle adapted to contain a so-called standard double width bed, which bed is normally wider than the door opening and through which door opening the bed may be passed, the bed being permanently mounted and the door and bed having a predetermined conjoint movement, or positionings, to permit the bed to be positioned completely within the receptacle, or without the same and to permit the single normal width door to completely close the opening when the bed is positioned in either of the aforesaid positions, and further to permit access to the receptacle so that it may be used for a clothes closet as well, when the bed is in either of the aforesaid positions.

The chief feature of the invention consists in a multiple hinge mounting for the door, and a hinge mounting for the bed, said bed and said door having a predetermined movement to permit the accomplishment of the foregoing object.

The full nature of the invention will be understood from the accompanying drawings and the following description and claims:

In the drawings Fig. 1 is a transverse sectional view through a receptacle and a portion of a room, associated with which is a single door shown in top plan, and a bed shown dotted and positioned within the receptacle, the door being shown in a second dotted position. Fig. 2 is a view similar to Fig. 1 except that the bed is positioned without the receptacle and the door is shown in full lines to illustrate the initial position of the door for closing the same behind the bed, the dot-dash line indicating a second position preliminary to closing the door behind the bed or permitting access to the interior of the receptacle, and the full dash line indicating the closed position of the door. Fig. 3 is a front view of the door opening with the door in closed position.

In the drawings 10 indicates a common wall between a room 11 and a receptacle such

as a dressing room 12 which usually is sufficiently large to receive in folded relation a so-called in-door bed 13. Any one of a number of standard beds of this general character is satisfactory.

The receptacle 12 communicates with the room 11 by way of a door opening 14. A single door 15 having the handle 16 is hingedly mounted as at 17 to a U-shaped frame having the vertical portion 18 and the top and bottom arms 19. The U-shaped frame is pivotally supported upon pivots 20 in brackets 21 and the connection therebetween is adjustable. The pivots 17 are in line with the front face of the door and for such purpose the vertical arm 18 includes a plurality of lateral projections 22 so that the door may lie immediately adjacent and substantially parallel to the U-shaped frame 19.

The bed 13 is suitably mounted by the transverse members 23 upon a suitable support such as the U-shaped member 24 and pivots 25. In the present instance the pivotal support for the bed is mounted upon the inside of the door frame opening, see Fig. 1, rather than upon either side thereof.

The distance between the two arms 19 is greater than the over all height of the bed when in the folded relation, as shown in Fig. 1. The distance that the vertical standard portion 18 is removed from the pivot 20 is sufficient to permit the bed 13, mounted in its mid-portion, to swing through the U-shaped door supporting frame and clear the same. The usual operation is to open the door by pulling upon the handle 16, see Fig. 1, move the door to the position shown dotted in that figure, then swing the bed through the door opening and through the frame or door support until the bed has assumed the position shown dotted in Fig. 2. The door is then pushed rearwardly with the frame from the dotted line position shown in Fig. 1 to the full line position in Fig. 2, and such rearward movement is continued until the edge of the door adjacent the knob 16 clears the end of the bed indicated at X. This occurs when the free edge of the door has moved substantially to the plane of the door opening. Thereupon the door may be moved upon its

hinges 17 toward the U-shaped frame, and then the U-shaped frame and door may be moved forwardly toward the door opening to position the door as shown by the dash lines in Fig. 2, to wit, closing said opening back of the bed. The width of the door casting is such that when the door is closed with the bed within the receptacle, the door is positioned forwardly of the bed support, as shown in Fig. 3, while if the door be closed behind the bed, as shown in Fig. 2, the door is positioned behind the bed support.

When the bed is positioned within the receptacle, as shown in Fig. 1, and access is desired to the dressing room for dressing purposes or to obtain garments therefrom, the door is opened in the usual manner and from the position shown in full lines in Fig. 1 to the dotted line position shown therein. When access is desired to the receptacle after the bed has been positioned without the same, the door and frame are both moved by pressure on the door from the position shown by the full dash lines in Fig. 2 to the position shown by the dot and dash lines in said figure.

The invention claimed is:

1. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, and means pivotally supporting the door at one edge and upon the opposite ends of said arms whereby said bed may be passed through said arms when the door is open, and said door may be passed behind the bed for closing said opening after the bed has passed through said opening from said receptacle.

2. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, and means pivotally supporting the door at one edge and upon the opposite ends of

said arms whereby said bed may be passed through said arms when the door is open, and said door may be passed behind the bed for closing said opening after the bed has passed through said opening from said receptacle, said door and arms when positioned behind said bed being swingingly movable into the receptacle to permit access thereto while the bed is positioned without the receptacle and in front of the door.

3. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, and means pivotally supporting the door at one edge and upon the opposite ends of said arms whereby said bed may be passed through said arms when the door is open, and said door may be passed behind the bed for closing said opening after the bed has passed through said opening from said receptacle, said door being arranged for movement forwardly from the receptacle and towards a transverse positioning relative to the opening when the bed is positioned within the receptacle to permit access to be had to the receptacle.

4. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, and means pivotally supporting the door at one edge and upon the opposite ends of said arms whereby said bed may be passed through said arms when the door is open, and said door may be passed behind the bed for closing said opening after the bed has passed through said opening from said receptacle, said door and arms when positioned behind said bed being swingingly movable into the receptacle to permit access thereto while the bed is positioned without the receptacle and in front of the door, said door

being arranged for movement forwardly from the receptacle and towards a transverse positioning relative to the opening when the bed is positioned within the receptacle to permit access to be had to the receptacle.

5. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, means pivotally supporting the door at one edge and upon the opposite ends of said arms whereby said bed may be passed through said arms when the door is open, and said door may be passed behind the bed for closing said opening after the bed has passed through said opening from said receptacle, and means adjustably mounting the pivoted ends of said arms.

6. In combination with a receptacle and a room communicating with each other through a normal width door opening, a single door for completely closing said opening, and a bed wider than the opening, of means pivotally supporting said bed adjacent the opening for swinging movement therethrough from the receptacle to the room and vice versa for predetermined positioning in either, a pair of arms pivotally supported at one end adjacent one vertical edge of the opening and of a length substantially equal to the width of the opening and positioned in spaced relation approximately at the top and bottom of the opening, means pivotally supporting the door at one edge and upon the opposite ends of said arms whereby said bed may be passed through said arms when the door is open, and said door may be passed behind the bed for closing said opening after the bed has passed through said opening from said receptacle, and means associated with the free ends of said arms and the pivotal support for said door off-setting the last mentioned pivotal support whereby said door may lie parallel to said arms.

7. In combination with a receptacle and a room communicating with each other through a normal width door opening, a single door for completely closing said opening, and a bed wider than the opening, of means pivotally supporting said bed adjacent the opening for swinging movement therethrough from the receptacle to the

room and vice versa for predetermined positioning in either, a pair of arms pivotally supported at one end adjacent one vertical edge of the opening and of a length substantially equal to the width of the opening and positioned in spaced relation approximately at the top and bottom of the opening, means pivotally supporting the door at one edge and upon the opposite ends of said arms whereby said bed may be passed through said arms when the door is open, and said door may be passed behind the bed for closing said opening after the bed has passed through said opening from said receptacle, and means connecting the free ends of said arms for forming a U-shaped swinging support therewith through which the bed may pass and against which the door may lie parallel thereto.

In witness whereof, I have hereunto affixed my signature.

ABRAHAM L. JONES.
